UNITED STATES PATENT OFFICE

153,789

DESIGN FOR A HOUSING FOR X-RAY TUBE
AND BLOWER

Edwin R. Goldfield and Ralph C. Schiring, University Heights, Ohio, assignors to Picker X-Ray Corporation, Waite Manufacturing Division, Inc., Cleveland, Ohio, a corporation of Ohio

Application May 25, 1948, Serial No. 146,595

Term of patent 14 years

(Cl. D26—5)

To all whom it may concern:

Be it known that we, Edwin R. Goldfield and Ralph C. Schiring, citizens of the United States and residents of University Heights, Cuyahoga County, Ohio, have invented a new, original, and ornamental Design for a Housing for X-Ray Tube and Blower, of which the following is a specification, reference being had to the accompanying drawing, forming a part thereof.

This application is a continuation in part of our prior application, Serial No. D124,523, filed December 8, 1945.

In the drawing, Figs. 1 and 2 are opposite side perspective views of a housing for X-ray tube and blower, showing our new design; while Figs. 3 and 4 are top and bottom plan views, respectively, of the same.

We claim:

The ornamental design for a housing for X-ray tube and blower, as shown.

EDWIN R. GOLDFIELD.
RALPH C. SCHIRING.
